UNITED STATES PATENT OFFICE.

DEROY AUSTIN, OF OMAHA, NEBRASKA.

SHOE.

1,055,695.

Specification of Letters Patent. Patented Mar. 11, 1913.

Application filed May 31, 1911. Serial No. 630,482.

To all whom it may concern:

Be it known that I, DEROY AUSTIN, a citizen of the United States, and a resident of Omaha, in the county of Douglas 5 and State of Nebraska, have invented certain new and useful Improvements in Shoes, of which the following is a specification.

My invention relates to the manufacture of shoes or footwear, and especially to the 10 construction and arrangement of insoles therein.

It is the object of my invention to provide a shoe having a flexible sole of gradually increasing hardness from its inner to 15 its outer part so that while the material adjoining the foot may be very soft and resilient the outer portions of the sole may have sufficient hardness and strength to make a durable structure.

20 A further object of my invention is to provide a cushion-soled shoe in which the cushioning material is prevented from displacement without the use of seams adjoining the foot.

25 Constructions embodying my invention are illustrated in the accompanying drawings, in which—

Figure 1 is a transverse section of a shoe constructed in accordance with my invention, Figs. 2, 3 and 4 are transverse sectional views showing different stages in the construction of the insole, and Fig. 5 is a detail showing a form of welt-feather different from that in Fig. 1.

30 In constructing a shoe in accordance with my invention I provide an outsole 1, upper 2 and welt 3 of ordinary form, material and arrangement. The insole is a composite structure consisting of alternate layers 35 of felt and canvas or strong fabric. A relatively soft and loose piece of felt is used for the upper layer 4, and the same is confined between the inner and intermediate sheets of canvas, 5 and 6, respectively. The 40 lower or outer felt layer 7 is relatively hard and compact, preferably the grade known as "piano felt". A canvas sheet 8 is preferably placed under the lower felt layer and said canvas or fabric sheet may be one impregnated with rubber and vulcanized so as to be waterproof. A sheet 9 of soft leather such as kid is placed over the inner canvas sheet 5 to form a cover or sock-lining.

45 In making up the insole the layer of soft felt, 4, is placed between the canvas sheets 5 and 6 and the three sheets secured to-

gether by a plurality of seams 10, as shown in Fig. 2. The sheet 9 of soft leather is then secured to the canvas sheet 5 by a seam 11 disposed beyond the edge of the 60 felt sheet, as shown in Fig. 3. The edges of the canvas sheets 5 and 6 are extended beyond the felt sheet 4 far enough to enable them to be carried down over the edges of the hard felt sheet 7, as shown in Fig. 4, 65 so that in making the welt-seam 12 the same may pass through said down-turned edges. The wale or welt-feather is thus formed by the edges of the canvas sheets 5, 6 and 8 and a portion of the felt sheet 7, of which the edge may be turned down as shown in 70 Figs. 1 and 4, or may have an incision made in the lower side thereof so as to form a marginal lip or flange through which the 75 welt-seam is passed as shown in Fig. 5.

It will be seen that when the insole is in place in the shoe, the edges of the kid lining 9 are drawn down around the edges of the felt sheet 4 so that the seam 11 is not exposed, and as the seams 10 are covered by 80 the sheet 9 there are no stitches visible on the inside of the shoe. The soft felt, being securely held by the stitching 10 between the sheets 5 and 6, is prevented from bunching up and being displaced when the shoe is 85 worn. The hard felt sheet 7, while contributing materially to the softness and flexibility of the sole, is sufficiently compact to resist any tendency to displace portions of the material and cause bunches or lumps 90 therein.

It will thus be seen that while the shoe constructed as shown is soft and yielding to the foot, and extremely flexible, yet the structure is one which is strong and durable, 95 having the transverse strength not only of the hard felt sheet 7 but also of the fabric sheets, especially the intermediate and lower or outer sheets 6 and 8.

Now, having described my invention, 100 what I claim and desire to secure by Letters Patent is:

1. In a shoe, an insole comprising alternate layers of felt and fabric, the different layers of felt being of different hardness, 105 and a welt-seam passing through one of the layers of felt and a plurality of the layers of fabric.

2. In a shoe, an insole comprising alternate layers of felt and fabric, the outer layer of felt being harder than the inner layer, and a welt-seam passing through the

layer of hard felt and the edges of the fabric layers.

3. In a shoe, an insole comprising a layer of hard felt, a layer of soft felt, and layers of fabric covering and lying between the layers of felt.

4. In a shoe, an insole comprising a layer of hard felt, a layer of soft felt, layers of fabric disposed between the layers of felt and on each side thereof, and a welt-seam 10 passing through the layer of hard felt and all the layers of fabric.

5. In a shoe, the combination with an upper and a welt, of an insole having an inner layer of felt, layers of fabric on each side thereof and stitched thereto, an outer layer of felt, and a seam passing through and securing together the welt, the upper, the layers of fabric and the outer layer of 20 felt.

6. In a shoe, the combination with an upper and a welt, of an insole having an inner portion, an intermediate fabric portion, and an outer felt portion, a seam se-

curing the inner portion to the intermediate 25 fabric portion, and a seam passing through and securing together the welt, the upper, the intermediate fabric portion and the outer felt portion.

7. In a shoe, the combination with an upper 30 and a welt, of an insole comprising a felt portion, a fabric portion disposed above the felt portion, and an inner portion disposed over the fabric portion, a seam securing the edge of the inner portion to the fabric only, 35 the edges of the fabric portion being turned down over the edges of the felt portion, and a seam passing through and securing together the welt, the upper, the edges of the fabric portion, and the edges of the felt 40 portion.

In testimony whereof I have hereunto subscribed my name in the presence of two witnesses.

DEROY AUSTIN.
